UNITED STATES PATENT OFFICE.

LYDIA LAMPERT, OF CHICAGO, ILLINOIS.

COLUMN CLAMP.

Application filed April 22, 1922. Serial No. 558,061.

To all whom it may concern:

Be it known that I, LYDIA LAMPERT, a citizen of the United States of America, and a resident of Chicago, county of Cook, and 5 State of Illinois, have invented a new and useful Improvement in Column Clamps, of which the following is a specification.

The main objects of this invention are to provide an improved clamp for concrete 10 molds particularly of the type used for forming columns; to provide an improved construction and arrangement of a flexible binding member adapted to embrace the mold; to provide improved tightening 15 means for drawing up the binding member; and to provide an improved connection of said binding member and tightening means with each other whereby they are compactly assembled for storage or shipment and are 20 quickly and easily arranged on the mold preparatory to being adjusted to clamp the mold parts in place.

An illustrative embodiment of this invention is shown in the accompanying drawing, 25 in which—

Figure 1 is a perspective view of a section of a mold for forming a concrete column, the mold parts being clamped in place by a clamping device constructed in accordance with this invention.

Figure 2 is a front elevation of the arrangement shown in Figure 1.

Figure 3 is a side elevation of a clamping device constructed in accordance with this 35 invention showing the compact arrangement of the same for storage or shipment purposes.

Figure 4 is a detail view of the arbor by means of which the clamping member is 40 drawn up.

A concrete mold clamp constructed in accordance with this invention involves the use of a flexible binding member adapted to embrace the mold, one end of which is secured 45 to an arbor permanently journaled upon a support adapted to rest against the mold and having the other end of the binding member detachably connected thereto, the arbor being arranged so as to draw the binding member up tight around the mold when in use 50 or to coil the binding member on the support when the device is to be shipped or stored. A pawl and ratchet is arranged on the support and arbor so as to lock the arbor in 55 position to hold the binding member as adjusted upon the mold.

In the specific embodiment herein shown a support 1 of channel shape has an arbor or shaft 2 journaled thereon to which one end of the flexible binding member 3 is secured so that, when the other end 4 of said binding member is extended around the mold 5 and detachably connected to said support 1, said arbor may be rotated for the purpose of drawing up the binding member firmly around the mold and retaining it in its adjusted position by means of a ratchet 6 and pawl 7.

The support 1 is preferably a channel-shaped member having flanges 8 and 9 which provide a support for the arbor 2. The holder may be either a metal stamping or a casting and is provided with aperture 10 adjacent one end of the base 11 thereof through which a nail may be driven for temporarily fastening the support to the mold 5 preparatory to extending the binding member 3 there-around.

The arbor 2 comprises a piece of shafting or a malleable casting of a length considerably greater than the distance between the flanges so that the ends thereof extend beyond said flanges when the arbor is placed in position. A nut 12 screwed onto one end thereof secures the arbor in place on the support so that it can be removed only in an axial direction when said nut is removed. The ratchet 6 may be separately constructed or formed integrally with the arbor and in either event is located on the outside of the flange 9 so that it coacts with the nut 12 to secure the arbor against axial movement. A slot 13 is formed in a medial part of the arbor through which one end of the band 3 is inserted and bent around the arbor so as to more or less permanently secure the arbor and the band together. The outer end of the arbor is squared as shown at 14 so as to enable a wrench or other tool to be applied thereto by which the arbor may be rotated.

The flexible binding member 3 is preferably in the form of a strip of sheet metal, the gauge of which depends upon the various sizes of molds with which the clamp is likely to be used. The strip being preferably wrought metal, it is more or less readily handled in either uncoiling it to pass it around the mold as shown in Figure 1 or in coiling it up as shown in Figure 2 when the device is to be stored or shipped. Suitable means are provided for connecting the end

4 of the band 3 to the support 1 after the band has been extended around the mold 5. A suitable form of means comprises an aperture 15 formed in the end 4 of the binding member which is adapted to engage a lug 16 extending inwardly from the base 11 of the support 1 adjacent the end thereof in which the aperture 10 is formed.

The pawl 7 is pivoted on the flange 9 in any suitable manner so that the end thereof properly engages the teeth on the ratchet 6 so as to enable the operator to lock the arbor 2 in place after it has been turned to properly tighten the binding member 3.

15 The tightening device, as we have shown and described, is used in substantially the following manner:

For shipment and storage purposes the binding member or band 3 is wound up on 20 the armor 2 as illustrated in Figure 3. The parts are thus all permanently secured together and are compactly arranged so as to occupy a comparatively small amount of space and also be always conveniently arranged and available for immediate use.

When the device is to be used the support 1 is secured upon the mold 5 in the proper place by driving a nail through the aperture 10 into the mold. The operator then grasps 30 the end 4 of the binding member 3 and carries it around the mold, the band in the mean while unreeling from the armor 2. The end 4 of the band is secured to the support 1 by having the aperture 15 therein placed 35 over the projection 16 on the support. A wrench or other tool is applied to the squared end 14 of the arbor and the arbor rotated so as to draw up the band firmly around the mold. Pawl 7 is thrown into position to 40 engage the ratchet 6 so as to lock the arbor in position so as to secure the band as adjusted around the form.

When the device is to be removed from the form, the pawl 7 is retracted which 45 releases the tension on the tightening member 3 and permits the operator to disconnect

the end 4 from the support 1. Thereupon a wrench or tool is applied to the squared end 14 of the arbor 2 and the band coiled up on the arbor preparatory to moving the device to another place for use or preparatory to temporarily storing same.

Although but one specific embodiment of this invention has been herein shown and described, it will be understood that numerous details of the construction shown may be altered or omitted without departing from the spirit of this invention as defined by the following claims.

I claim:

1. A clamp for concrete molds comprising a support, a single arbor journaled thereon, so as to be removed from said support only by dismantling the clamp, a flexible binding member permanently attached at one end to said arbor, and having its other end normally free, co-acting means on said support and said other end of said strap, whereby said strap may be detachably connected to said support after having been wrapped 70 around a mold and then being drawn up tight by said arbor, and means for locating said arbor to hold said binding member in its drawn-up position.

2. A clamp for concrete molds comprising 75 a channel-shaped support, an arbor spanning the parallel flanges of said support and journaled thereon adjacent to the upper edges and removable therefrom only in an axial direction, a flexible binding member 80 secured to said arbor between said flanges and adapted to be placed around the mold, a projection on the base of said support, said binding member having a recess formed in the other end thereof adapted to engage 85 said projection for connecting said member and support together, and pawl and ratchet mechanism for securing said arbor to hold said member in its adjusted position.

Signed at Chicago this 20th day of April, 90
1922.

LYDIA LAMPERT.
